UNITED STATES PATENT OFFICE.

WALDO C. NEILY, OF CANAAN, NEW HAMPSHIRE.

COMBINED IRONING-BOARD AND STEP-LADDER.

1,131,943.

Specification of Letters Patent. Patented Mar. 16, 1915.

Application filed May 20, 1914. Serial No. 839,826.

To all whom it may concern:

Be it known that I, WALDO C. NEILY, a citizen of the United States, residing at Canaan, in the county of Grafton and State 5 of New Hampshire, have invented certain new and useful Improvements in Combined Ironing-Boards and Step-Ladders, of which the following is a specification, reference being had to the accompanying drawings.

10 This invention relates to a combined ironing board and step-ladder; and it has for its object the provision of an article of this character consisting of parts capable of being adjusted so as to permit one to readily 15 convert the device from an ironing board to a step-ladder or vice versa as the occasion may demand.

Another object of the invention is the provision of an article of this character, consisting 20 of folding parts whereby the device may be arranged in a relatively compact package for shipment or storage or placed in a small space when not in use.

A further object of the invention is the 25 provision of an article of this character which will be constructed so as to maximize the stability of the device when used as an ironing board and prevent the parts of the structure from rocking.

30 With these and other objects in view, the invention consists of certain novel features of construction, combination and arrangement of parts, as will be hereinafter described and claimed.

35 In the accompanying drawings:—Figure 1 is a side view of the device, showing the same adjusted to form an ironing board; Fig. 2 is a similar view, showing the device adjusted to form a step-ladder; Fig. 3 is a view, showing the device in its complete 40 folded position; and Fig. 4 is a section on the line 4—4 of Fig. 1.

The device comprises a board 1 and ladder frame 2, the said frame being preferably 45 formed of side members 3, 3 connected with each other by the usual rounds or steps 4, and at the top the members are connected by a supporting ledge 5 which may be used to support articles upon when one is using 50 the ladder. The said rest or ledge 5 is hinged to one end of the board 1, as at 6, so that the board may be adjusted to lie in parallel relation with the frame 2, as shown in Fig. 3.

55 On reference to Fig. 1, it is seen that the board 1 and the frame 2 are adjusted so that

the device will assume the form of an ironing table, and, in order that the board may be made to maintain the required ironing position and be secured in a state of rigidity 60 during the ironing operation, I prefer to employ braces 7 interposed between the board 1 and the frame 2, and each consisting of companion pivot bars 8 and 9, the latter having pivotal connection at 10 with 65 the frame 2, and the former having pivotal connection at 11 with the board 1. A transverse brace bar 12 is slideable upon the bars 8 and 9, and it is provided with socket members 13 at its ends that are adapted to pass 70 over the points of connection of the bars 8 and 9 with each other and to prevent the bars 8 and 9 from breaking at their joints when the board 1 is set up to the position shown in Fig. 1. To secure the brace bar 12 75 in the position just referred to, a set screw 14 is employed, being carried by one of the socket members 13 and having detachable connection or clamping engagement with the adjacent bar 9.

80 When the device is adjusted to the position of an ironing table, the lower end 15 of the frame 2 is adapted to rest directly against the floor, and the frame 2 assumes a substantial diagonal position. In order 85 to maintain a horizontal position of the board 1 I provide side supporting legs 16, whose lower ends are adapted to rest against the floor, while the upper ends are pivoted at 17 to the frame 2. The legs 16 are held 90 in proper supporting positions by means of brace bars 18 pivoted upon the frame 2, as at 19. The pivots 19 are offset from the lines of the pivots 17 for a purpose to be hereinafter described. The bars 18 are 95 provided at their free ends with hooks 20 that are adapted to be interchangeably connected with pins 21 and 22 on the legs 16 and the frame 2 respectively. When the hooks are engaged with the pins 21, latch 100 devices 23, which are slideable on the braces 18, are adapted to be extended over the open side of the hooks and to thereby confine the braces upon the pins, as will be understood. When the several parts are as- 105 sociated in the specified manner the board 1 is held in a substantially rigid condition, and the device as a whole is held against undue rocking when the board is used for ironing purposes.

110 When the device is not in use, the hooks 20 are disconnected from the pins 21 and the

bars 18 are first swung into engagement with the pins 25. The latches 23 are then swung over the open sides of the hooks so as to hold the bars 18 against swinging movement from the sides of the frame 2. The legs 16 are then swung against the sides of the frame and the recesses 24 near the lower ends of the legs are made to receive pins 22 upon the sides of the frame 2. The latches 10 26 are then swung over the open end of the recesses 24 and over one side of the pins 22. This holds the legs 16 against the sides of the frame 2, as will be understood. The final folding of the structure is effected by 15 releasing the set screw 14 and sliding the brace bar 12 to a point at one side of the joints between the bars 8 and 9. The bars 8 and 9 are then folded so as to cause the bar to assume the position shown in Fig. 3.

20 What is claimed is:

1. A device of the class described comprising a frame, a board pivoted to one end thereof, legs carried by the frame, braces carried by the frame, means carried by the 25 braces to hold the same in folded and extended positions, supporting bars pivotally connected together and having their outer ends pivotally connected to the board and frame, sleeves slidably mounted upon the 30 supporting bars and carrying a set screw adapted to engage the pivot joint to hold

the bars against pivotal movement, and latches carried by the legs adapted for engagement with the frame whereby the legs are held in a folded position. 35

2. A device of the class described comprising a frame, a board pivoted to one end thereof, supporting legs carried by the frame, pins arranged intermediate of the ends of the legs, bracing members carried 40 by the frame, hooks formed upon the free ends of the brace members adapted for engagement with the pins, slideable bolts carried by said ends whereby the hooks are held into engagement with the pins, means 45 whereby to hold the brace members and legs in a folded position, supporting bars pivotally connected together and having outer ends pivotally connected to the frame and board, a transverse member having 50 sleeves formed on its ends slidably arranged on the supporting bars, and set screws carried by the sleeves adapted for engagement with the pivot joint to hold the bars against pivotal movement. 55

In testimony whereof I hereunto affix my signature in the presence of two witnesses.

WALDO C. NEILY.
